UNITED STATES PATENT OFFICE.

HUBERT VAN ZANDT, OF HINSDALE, AND BRADFORD EYMAN, OF WINNETKA,
ILLINOIS.

WASHING DEVICE.

Application filed August 6, 1924. Serial No. 730,394.

This invention relates to washing machines or devices, and more particularly to those adapted for washing dishes, or for similar purposes.

Generally stated, the object of the invention is to provide novel and improved construction whereby the supply of water to a fountain brush of this kind for washing dishes, or for similar purposes, can be controlled at will, for different purposes, thereby to facilitate the use of the device for either washing or rinsing the dishes or other things to be washed.

A special object is to provide a novel and improved form of valve in the head of the device, whereby the water can be discharged from either side of the head, as may be desired.

Another object is to provide novel and improved means for holding the cage or box in which soap is contained for soaping the water.

Another object is to provide novel and improved means for detachably holding a sponge or other washing means in position to receive water from the head of the device.

It is also an object to provide certain details and features of construction and combinations tending to increase the general efficiency and the desirability of a washing device of this particular character.

To the foregoing and other useful ends the invention consists in matters herein-after set forth and claimed and shown in the accompanying drawings, in which

Figure 1 is a side elevation of a washing device embodying the principles of the invention, showing the same adapted more particularly for washing dishes.

Figure 2 is an enlarged longitudinal section of said device, with a portion of the handle shown broken away for convenience of illustration.

Figure 3 is a plan of the head of the device, on the same scale as Figure 2.

Figure 4 is a detail section on line 4-4 in Figure 2.

Figure 5 is a detail section on line 5-5 in Figure 2.

As thus illustrated, the invention comprises a metal head 1 which is substantially flat and which is provided on one flat side thereof with apertures 2, and which is provided on the other flat side with similar

apertures 3 whereby the water can be discharged from either side of this head.

The stem or neck 4 of this head is removably held in a tube 5, as by screw 6, and this tube is rigid with a hollow handle 7 to which a hose pipe 8 is connected to supply water. The tube 5 has a transverse slot 9 at one side thereof for the handle 10 which is rigid with the tubular valve 11, the latter having its discharge end partially closed at 12, whereby a discharge opening 13 is formed of one half the diameter of the interior of the valve, which diameter is the same as that of the tube 14 in the handle, the same as that of the stem of neck 14 previously mentioned. The head 1 is provided with a partition 15 situated substantially midway between the two sides of the head, so that one chamber 16 is provided through which water may pass and be discharged through the openings 2, and another chamber 17 through which the water may pass and be discharged through the openings 3 previously mentioned. By swinging the handle 10 in the slot 9 the discharge opening 13 of the valve can be brought opposite either the chamber 16 or the chamber 17 thereby to discharge the water from either side of the head.

The soap cage or box 18 is of wire gauze, preferably, and has a removable cover 19 to permit insertion of the soap. The means for holding the cage or box in position on the head of the washing device may be of any suitable character. Preferably, as a matter of further and special improvement, spring strips 19 are provided and rigidly connected together by a ring 20, these spring strips being bent to provide inclined shoulders 21 and 22 to hold the soap cage or box in place. The lower ends of these strips 19 have portions 23 to engage and hold the head 1, the latter having notches 24 to receive these portions of the spring strips. The upper portions of the strips 19 are bent outwardly as shown, and are provided with screw fastening devices 25 to grip portions of the sponge 26, or any other washing means, so that the washing means can be attached at will. Thus the soap box or cage 18 can be removed from the strips 19, by forcing either the upper or lower ends of the strips outward, and these strips can be swung outward at their lower ends to dis-

engage them from the head 1 of the washing device.

The device can be used, by turning the valve, to discharge water from the chamber 17 through the apertures 3 and through the soap box or cage to the sponge, thus producing soapy water for use in washing the dishes or other things. Thereafter to rinse the dishes or other things, the valve can be reversed to cause the water to discharge from the chamber 16 through the apertures 2, in the form of a spray. The sponge 26 or other washing means can be renewed whenever necessary. The device can be easily washed and kept clean. In addition, the construction is intended to minimize the danger of breakage, and to insure operation and use of the device in a satisfactory manner.

The removable cover 19 of the soap box 20 or cage is held in place by the inclined shoulders 21, it will be seen, so that the box and its cover are held together by the devices for mounting the box on the head or nozzle. The axis of the valve 11, it will be seen, extends longitudinally of the handle 7, and the valve is oscillatory about this axis, at a point between the handle and the head or nozzle, to control the supply of water in the manner shown and described.

30 What we claim as our invention is
1. In a fountain washer, a handle having a water connection thereto, a head forming a rigid discharge nozzle on the end of said handle, washing means, an attaching device 35 for supporting said washing means in position on said head, in open spaced relation from one side thereof, so that water discharged from said head will be supplied to the object to which the washing means is applied, said attaching device comprising members supported on said head, means on the ends of said members for detachably grip-

ping said washing means, and a soap box in the form of a wire cage removably held in place by said members, in open spaced relation between said head or nozzle and said washing means, whereby to soap the water supplied to said washing means.

5 2. A structure as specified in claim 1, said members comprising flexible spring arms detachably engaging said head disengageable therefrom by flexing the arms out of engagement therein.

3. A structure as specified in claim 1, the middle portions of said members being rigidly connected together by a ring, so that the end portions of said members are free to flex or bend outwardly, the end portions of said members detachably engaging said head, and the other ends of said members being provided with means detachably gripping said washing means.

4. In a washer, the combination of a handle, having a water supply connection, a discharge head on said handle, washing means disposed at one side of said head, means for soaping the water, for said washing means, comprising a box for holding soap, with openings in the walls of said box, means supporting said washing means in position to receive the discharge from one side of the head, said supporting means comprising spring devices carried by the head and detachably holding said box in spaced relation from one side of said head, in position to receive the discharge from said head.

5. A structure as specified in claim 4, said box having a removable cover engaging said devices to hold said cover and box together.

Specification signed this 2nd day of 80
August, 1924.

HUBERT VAN ZANDT.
